CLAIM

The ornamental design for a hand warmer, as shown and described.

DESCRIPTION

FIG. 1 is a front and top perspective view of a hand warmer, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in a using position.

The broken lines in the figures illustrate portions of the hand warmer that form no part of the claimed design. The broken lines of another hand warmer in FIG. 9 shown in the drawings depict environmental structure that form no part of the claimed design.

1 Claim, 9 Drawing Sheets
